UNITED STATES PATENT OFFICE

BENJAMIN F. MIESSNER, OF SHORT HILLS, NEW JERSEY

ELECTRODYNAMIC SOUND-REPRODUCING SYSTEM

Application filed March 6, 1929. Serial No. 344,883.

The present invention relates to sound reproducing systems, and particularly to such systems employing signal reproducing devices requiring energizing for operation, such as the so-called electrodynamic type of reproducer.

An object of the invention is to energize a reproducer requiring a strong magnetic field from a readily available source of unsteady current, such as rectified alternating current of a commercially available 60 cycle source, without encountering an annoying degree of hum.

A further object is to employ the current of a filter system associated with an alternating current rectifier as a source for energizing a system of vacuum tube amplifiers in the additional function of energizing the reproducer associated with the system, while keeping 20 hum effects adequately small to be non-disrupting.

The invention is readily understood from the following description with the aid of the figures of the accompanying drawing in 25 which like reference characters represent like parts so far as possible in the several figures.

Fig. 1 is an illustration in diagram of an electrodynamic form of sound reproducer connected to employ my invention.

Fig. 2 illustrates a modification of the arrangement of Fig. 1.

Fig. 3 diagrammatically illustrates an electrodynamic reproducer associated with a filter system in a manner to employ features of 35 my invention.

Fig. 4 illustrates a modification of the arrangement of Fig. 3.

Referring to Fig. 1, the usual electrodynamic reproducer is shown as having a 40 magnetic core M on which is wound an energizing or field producing coil F. A movable or armature coil A is shown associated with the field of the core M, and having attached thereto a cone C or other suitable sound generator.

The field coil F is shown energized from an alternating current source through a suitable transformer T₁ by way of a rectifier D, which may be either a full wave or single wave rectifier of suitable kind, such as a tube rectifier

or an electrolytic rectifier, both kinds being so used.

The armature coil A is shown energized by the signal currents to be reproduced as sound through a transformer T₂, which may be for instance the output element of a cascaded amplifier system. The signal currents flowing through coil A react on the field produced by coil F to produce motion of coil A and attached cone C in accordance with the sound representing signal currents. However, the rectified field energizing current through coil F is not steady, thus producing an unsteady field tending to produce hum reproducing motion of coil A. This I oppose by introducing a selected amount of current of the same character as that in field coil F into armature coil A by way of coupling resistance R, the amount of current being selected in any desired way, as by a tap S on resistance R, which tap may be permanently set once the desired adjustment is found. The connection of the coil A to the resistance R is so poled that the effect of the fluctuating current in coil A opposes the effect of the fluctuating current in coil F.

The device of course can be used in fashion reverse to that of sound reproduction; that is, as a sound pick-up or microphone, in which case creating sound in the vicinity of cone C 80 sets the coil A in motion to generate sound representing currents which may be passed to an amplifier or other device through transformer T₂.

In Fig. 2 I show a transformer T₃ substituted for the resistance R of Fig. 1 for transferring the hum-bucking energy to coil A, in this way avoiding introducing any of the direct current component into the coil A circuit. Of course an auto-transformer, or any other 90 suitable form of coupling between the two circuits may be used. Other than this coupling, Fig. 2 is the same as Fig. 1.

In Fig. 3 I show the field coil F of the reproducer used as the choke coil of a filter system of general character, shown to have filter condensers C₁ and C₂. The filter is shown fed from the usual rectifier system having a rectifier tube D energized through secondaries S₁ and S₂ of a transformer T₁ connected into 100 .

an alternating current supply system. The filter system is shown to supply a load E, conventionally shown, which may be for example the plate circuits of a cascaded series of vacuum tubes.

As before the reproducer is shown to have a movable coil A associated with a reproducing cone C. Input of sound representing current to coil A is by way of transformer T₂, which may be for instance the output of an amplifier system the plate circuits of the tubes of which form the load E on the filter system.

I show a resistance R, coupling the movable coil circuit with the filter circuit, so that some of the same character of current that flows through coil F is introduced into coil A for hum neutralizing as described in connection with Fig. 1, it being understood that the circuits may be coupled by a transformer as in Fig. 2, or through other suitable form of coupling. In Fig. 3 the field coil F serves the additional useful function of acting as a filter choke, thereby saving from the system the weight and cost of such an element.

In Fig. 4 I show for example the output tube VT of a cascaded amplifier system connected to the same supply and filter system of Fig. 3 for energizing the plate circuit thereof, the input circuit being shown to include as a sound representing current input element a transformer T₃, which may be the output of a series of cascaded tubes also energized by the filter system.

The energizing of the filament and grid electrodes of tube VT is shown in accordance with standard practice, and requires no detailed description, not being a feature of the present invention.

In this Figure 4 arrangement I show the armature coil A of the reproducer energized with sound representing currents from the output of tube VT through transformer T₂. For hum bucking I provide a coil B associated with core M to pick up some of the fluctuations due to unsteady current through field coil F, and introduce these hum bucking currents into armature coil A by way of the grid circuit of tube VT, and thus, after amplification, into transformer T₂ to coil A, and of course can pole either transformer T₂ or coil B to get the desired neutralizing phase. I show coil B to have a tapped connection S, but this may be determined and permanently fixed by the design of the coil in a given design.

The adaptation of the features of my invention to various like systems will be apparent to those practiced in the art from the description I have given, and I intend no limitations by reason of having confined my description to a limited number of typical examples of its employment, the scope of the invention being set forth in the accompanying claims.

Having thus described my invention, what I claim is:

1. In a device for translating electrical signal energy into sound energy, the combination of a source of alternating current energy, a rectifier for converting said alternating current into unidirectional current having a ripple component, a coil connected between the electrodes of said rectifier whereby a strong magnetic field of constant polarity is developed around said coil, a conductive element mounted for vibrational movement within said field, means for passing signal currents through said conductive element whereby said conductive element is vibrated at the signal current frequency, and means for transferring a regulable portion of said ripple component of the unidirectional current from said source to said conductive element, of a phase to substantially eliminate vibration of said conductive member by the variation in field intensity caused by the ripple component of said unidirectional current.

2. In a device for translating electrical signal energy into sound energy, the combination of a source of alternating current energy, a rectifier for converting said alternating current into unidirectional current having a ripple component, a coil connected between the electrodes of said rectifier whereby a strong magnetic field of constant polarity is developed around said coil, a conductive element mounted for vibrational movement within said field, means for passing signal currents through said conductive element whereby said conductive element is vibrated at the signal current frequency, means for diverting a regulable portion of said ripple component of said unidirectional current from said coil, and means for introducing this diverted portion into said conductive element of a phase to substantially eliminate vibration of said conductive member by the variation in field intensity caused by the ripple component of said unidirectional current.

3. In a device for translating electrical signal energy into sound energy the combination of a source of alternating current energy, a rectifier for converting said alternating current into unidirectional current having a ripple component, a coil connected between the electrodes of said rectifier whereby a strong magnetic field of constant polarity is developed around said coil, a conductive element mounted for vibrational movement within said field, means for passing signal currents through said conductive element whereby said conductive element is vibrated at the signal current frequency, a second coil coupled to the coil-rectifier circuit for diverting a regulable portion of the ripple component of said unidirectional current therefrom, and means for introducing this diverted portion into said conductive element of a phase

- to substantially eliminate vibration of said conductive member by the variation in field intensity caused by the ripple component of said unidirectional current.
5. In a device for translating electrical signal energy into sound energy the combination of a source of alternating current energy, a rectifier for converting said alternating current into unidirectional current having
- 10 a ripple component, a coil connected between the electrodes of said rectifier whereby a strong magnetic field of constant polarity is developed around said coil, a conductive element mounted for vibrational movement
- 15 within said field, means for passing signal currents through said conductive element whereby said conductive element is vibrated at the signal current frequency, a second coil coupled to the coil-rectifier circuit for diverting a regulable portion of the ripple component of said unidirectional current therefrom, a third coil conductively coupled to said element and associated with said second coil for introducing this diverted portion into said
- 5 conductive element of a phase to substantially eliminate vibration of said conductive member by the variation in field intensity caused by the ripple component of said unidirectional current.
5. In a device for translating electrical signal energy into sound energy the combination of a source of alternating current energy, a rectifier for converting said alternating current into unidirectional current having
- 10 a ripple component, a coil connected between the electrodes of said rectifier whereby a strong magnetic field of constant polarity is developed around said coil, a conductive element mounted for vibrational movement within said field, means for passing signal currents through said conductive element whereby said conductive element is vibrated at the signal current frequency, a second coil coupled to the coil-rectifier circuit for diverting therefrom a regulable portion of the ripple component of said unidirectional current, a vacuum tube having a grid, filament and plate, said second coil being connected to said grid, a transformer, the primary of which connects said plate to said coil-rectifier circuit, the secondary of said transformer being associated with said conductive element of a phase to substantially eliminate vibration of said conductive member by the variation in field intensity caused by the ripple component of said unidirectional current.

In witness whereof, I have hereunto subscribed my name this first day of March, 1929.

BENJAMIN F. MIESSNER.
